United States Patent Office

Des. 193,358
Patented Aug. 7, 1962

193,358

GRILLE UNIT

Edward C. Hallock, 86 Woodland Ave., Summit, N.J.

Filed Jan. 10, 1962, Ser. No. 68,245

Term of patent 14 years

(Cl. D54—2)

I claim:

The ornamental design for a grille unit, as shown.
